US0D1084554S

(12) **United States Design Patent** (10) **Patent No.:** **US D1,084,554 S**
(45) **Date of Patent:** **** Jul. 15, 2025**

(54) **PET WASTE SCOOP ASSEMBLY**

(71) Applicant: **Towerstar Pets, LLC**, Malvern, PA (US)

(72) Inventors: **Fernando Becattini, Jr.**, Malvern, PA (US); **Jacquelyn N. Becattini**, Malvern, PA (US); **Fernando Becattini, Sr.**, Devon, PA (US); **Ryan Rutherford**, Pittstown, NJ (US)

(73) Assignee: **TOWERSTAR PETS, LLC**, Malvern, PA (US)

(**) Term: **15 Years**

(21) Appl. No.: **29/967,204**

(22) Filed: **Oct. 9, 2024**

(51) LOC (15) Cl. **30-11**

(52) U.S. Cl.

USPC **D30/162**

(58) **Field of Classification Search**

(57) **CLAIM**

The ornamental design for a pet waste scoop assembly as shown and described.

DESCRIPTION

FIG. 1 is a front, top, right side isometric view of a pet waste scoop assembly in accordance with our design;

FIG. 2 is a front, top, left side isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings represent portions of the pet waste scoop assembly that form no part of the claimed design.

1 Claim, 8 Drawing Sheets
